UNITED STATES PATENT OFFICE.

LEE D. HINCHER, OF SHOALS, INDIANA, ASSIGNOR TO HINCHER MANUFACTURING CO., INCORPORATED, OF SHOALS, INDIANA.

DISPLAY-RACK.

1,127,002.

Specification of Letters Patent.

Patented Feb. 2, 1915.

Application filed October 22, 1912. Serial No. 727,103.

To all whom it may concern:

Be it known that I, LEE D. HINCHER, a citizen of the United States, residing at Shoals, Indiana, have invented certain new and useful Improvements in Display-Racks, of which the following is a specification.

This invention relates to improvements in display racks.

My improvements relate particularly to 10 the type of racks having standards or uprights and bars extending between the same for the support of clothing and the like.

The main object of this invention is to 15 provide an improved display rack which may be shipped in the knockdown or disassembled condition and quickly and easily set up by the user, and one which, when set up, is very strong and rigid and has a complete and finished appearance.

Further objects, and objects relating to 20 structural details, will definitely appear from the detailed description to follow.

I accomplish the objects of my invention by the devices and means described in the following specification.

25 The invention is clearly defined and pointed out in the claims.

A structure which is a preferred embodiment of my invention is clearly illustrated in the accompanying drawing forming a 30 part of this specification, in which: Figure I is a perspective view of a structure embodying the features of my invention. Fig. II is an enlarged detail vertical section on a line corresponding to line 2-2 of Fig. I. Fig. III is an enlarged detail vertical section on a line corresponding to line 3-3 of Fig. I. Fig. IV is a detail perspective view of one of the bars with a coupling member thereon.

40 In the drawing, similar reference characters refer to similar parts throughout the several views, and the sectional views are taken looking in the direction of the little arrows at the ends of the section lines.

45 Referring to the drawing, the standards 1 are provided with cross arms 2 at their upper ends and braces 3, the braces being provided with casters 4.

The rack bars 5 are mounted on the cross 50 arms 2 of the standards. The bars 5' at the lower end of the standards are bracing and supporting bars but are the same and pro-

vided with the same coupling members as the supporting bars 5.

The coupling members 6 are provided with threaded sockets 7 at their outer ends for the bars 5 which are threaded at both ends. At their inner ends, the coupling members are provided with bosses 8 squared or otherwise shaped, to receive a wrench. The coupling members are also provided with threaded axial openings 9 at their inner ends adapted to receive attaching bolts. The coupling members are suitably 60 conformed to abut the sides of the standards and to provide an ornamental finish for the ends of the bars.

The standards are provided with seats 10 for the bosses 8 of the coupling member. 70 The intermediate upright is provided with pairs of oppositely disposed coupling members, a single bolt 11 threaded at both ends securing the two coupling members. The coupling members of the outer standards are 75 secured by bolts 12 arranged through the standards from the outside of the same, as clearly shown in Fig. III.

In practice, the racks are shipped in the knockdown with the coupling members assembled on the central standard and on the outer ends of the bars. In assembling, the bars are screwed into the sockets on the central standard by means of a wrench on the bosses 8. The outer standards are then secured by means of the bolts 12.

It will be seen that a wrench is the only tool required. The structure when assembled is very strong and rigid and has a finished appearance.

Having thus described my invention, what I claim is new and desire to secure by Letters Patent is:

1. A rack comprising end standards and an intermediate standard; bars threaded at their ends; coupling members having threaded sockets for said bars at their outer ends and bosses at their inner ends adapted to receive a wrench, the inner ends of the said coupling members being threaded to receive 95 attaching bolts, the standards being provided with seats adapted to receive said bosses, the intermediate standard having opposed seats, there being a pair of such coupling members disposed oppositely in said 100 seats on said intermediate standard, a bolt 105

threaded at each end arranged through said intermediate standard and threaded into said opposed coupling members, and bolts arranged through said end standards from

5 the outer sides thereof and threaded into the coupling members at the outer ends of the bars.

2. A rack comprising standards; bars threaded at their ends; coupling members 10 having threaded sockets for said bars at their outer ends and bosses at their inner ends adapted to receive a wrench, so that a bar with a coupling member thereon may be turned with a wrench engaged with the boss 15 of a coupling member, the inner ends of the said coupling members being axially threaded to receive standard attaching bolts, the standards being provided with seats adapted to receive said bosses; and bolts arranged 20 through said standards and threaded into said coupling members.

3. In a structure of the class described, the combination with a standard; a bar threaded at its end; a coupling member having a 25 threaded socket at its outer end adapted to receive said bar and a centrally disposed boss at its inner end adapted to receive a wrench so that a bar with a coupling member thereon may be turned with a wrench engaged 30 with the boss of a coupling member, and a

bolt arranged through said standard and threaded into said socket, said standard being provided with a seat for said boss.

4. In a structure of the class described, the combination with a standard; a bar 35 threaded at its end; a coupling member having a threaded socket at its outer end adapted to receive said bar and a centrally disposed boss at its inner end adapted to receive a wrench so that a bar with a coupling member 40 thereon may be turned with a wrench engaged with the boss of a coupling member, and a bolt arranged through said standard and threaded into said socket.

5. A structure of the class described comprising a standard; bars threaded at their ends; coupling members having threaded sockets at their outer ends for said bars, the inner ends of said coupling members being axially threaded to receive an attaching 50 bolt; and a bolt threaded at each end arranged through said standard and threaded into said coupling members.

In witness whereof, I have hereunto set my hand and seal in the presence of two witnesses.

LEE D. HINCHER. [L. S.]
